The United States of America,

To all to whom these Letters Patent shall come:

Whereas

the United States, hath alleged that he has invented a new and useful improvement such improvement he states has not been known or used before his invention, and that he does hereby believe that he is the true inventor or discoverer of the said improvement, has paid into the treasury of the United States, the sum of three dollars, delivered a receipt for the same, and presented a return to the Secretary of State, containing a description of claiming an exclusive property in the said improvement, and paying that a patent may be granted for that purpose. These are therefore to grant, according to law, to the said John C. Frémont his heirs, administrators, & assigns, for the term of fifteen years, from the 1848 day of January the full and exclusive right and liberty of making, constructing, using and vending to others to be used, the said improvement, as described and set forth in the words of the said patent, to be granted by the undersigned being signed, and made a part of these premises:

In testimony whereof, I have caused these Letters to be made Public, and the Seal of the United States to be hereto affixed.

Given under my hand, at the city of Washington, the 1848 day of January in the year of our Lord one thousand eight hundred and forty-eight and of the independence of the United States of America, the thirty-first

BY THE PRESIDENT

John C. Frémont Secretary of State

City of Washington, D. C.

I, ROBERT C. CECILY, that the foregoing Letters Patent, were delivered to me at the 1848 day of January in the year of our Lord forty-eight and of the independence of the United States of America, and that I have examined the same, and find them correct in all respects, and I do hereby return the same to the Secretary of State, remitting therefor the sum of one thousand dollars, on the thirty-first day of January in the year aforesaid.
